UNITED STATES PATENT OFFICE.

JOHN KELLY, OF NORFOLK, VIRGINIA, ASSIGNOR TO KELLY BUTTON MACHINE COMPANY, INC., OF NORFOLK, VIRGINIA, A CORPORATION OF VIRGINIA.

BUTTON-FEEDING INSTRUMENTALITY FOR BUTTON-SETTING MACHINES.

1,398,026.

Specification of Letters Patent.

Patented Nov. 22, 1921.

Application filed October 6, 1915. Serial No. 54,365.

To all whom it may concern:

Be it known that I, JOHN KELLY, a citizen of the United States, residing at Norfolk, in the county of Norfolk and State of Virginia, have invented certain new and useful Improvements in Button-Feeding Instrumentalities for Button-Setting Machines, of which the following is a specification, reference being had therein to the accompanying drawing.

This invention pertains to an improvement in button feeding instrumentalities designed for use in button setting machines. The invention is adapted particularly for employment in connection with a type of machines wherein a coil of wire is placed in juxtaposition to wire feeding instrumentalities, which instrumentalities automatically advance the wire through the eye of a button. Such machines are provided with means for forming the wire into staples, forcing the staples through the material, and finally clenching the same.

In this particular art it has been customary to employ a raceway or feed tube designed for conducting the buttons serially to a point where the staple wire will be accurately fed therethrough. The wire is fed through by mechanism operated by a foot treadle, the severing mechanism, the forming die and the forming mechanism being associated with the foot treadle or power lever, the operation being performed consecutively and so by one stroke of the power lever or treadle.

Such machines have been illustrated in various earlier patents, among which may be mentioned the patent to Olds and Ekland No. 368419. The present invention contemplates improvements primarily in the button feeding and button controlling instrumentalities.

More specifically stated, the present invention comprehends a button feed or chute so constructed and arranged that the same may be adjusted for different size button heads. It comprehends also the provision of instrumentalities for positively holding the button against snapping out or displacement when the same is in position to receive the staple forming wire.

The invention also comprehends certain improvements whereby this positive holding means is released at the proper interval and in addition thereto suitable yielding means for maintaining the next succeeding button in position for advancement at the proper time.

There is illustrated in the accompanying drawing an improvement in the button hopper wherein the same may be rotated so that different sized or different styles of buttons may be fed to the machine, the hopper being a duplex one and at the same time so jointed with the standard or support that the hopper may be tipped to discharge its contents should it be desired to replace one type of button with that of another.

In the accompanying drawing a machine embodying the invention is depicted, but it is to be understood that various changes, alterations and modifications can be made without departing from the nature and principle of the invention presently to be described and to be defined in the claims.

Figure 1 represents a side elevation of what is termed the head of the button setting machine, the standard which is of the usual type, being omitted;

Fig. 2 is a plan view of the head showing the button hopper broken away;

Fig. 3 is a similar view on an enlarged scale showing the movable raceway cap thrown back;

Fig. 4 is a section centrally through the raceway showing the near side of the head broken away or in section;

Fig. 5 is a detail fragmentary view of the head of the machine showing the raceway but with the wire supporting bracket removed;

Fig. 6 is a section on the line 2—2 of Fig. 2;

Fig. 7 is a front elevation of the head showing the rear portion of the raceway broken away and the clenching die supporting arm in section;

Figs. 8, 9 and 10 are details of the button feed and clamping instrumentalities.

The standard A, base B and operating rod C, as shown in Fig. 4, are of the usual construction, the standard being supported

on suitable legs and the operating rod C being connected with the treadle mechanism, as is usual in this art. Mounted in the head between the supporting legs thereof is a 5 rock arm C' to which the operating rod C is connected. This operating arm is in the form of a bell crank and has at its upper end a link connection C² with staple cutting, forming and setting mechanism. This 10 staple forming and setting mechanism includes a rocking member C³ and a suitable spring operated clamping jaw C⁴. These parts are all illustrated and described in my application for Letters Patent Serial No. 15 864895, filed October 3, 1914, and need not further be described.

Projecting upwardly from the cap plate of the head is an inclined raceway part D, having a formed button eye receiving groove 20 d extending through the same from end to end. The lower end of the raceway terminates adjacent the wire feed opening of the machine and the button eye clamping and positioning jaw C⁴.

25 Positioned at one side of the raceway member D is a series of projections d', which carry on their upper ends a plate D', the latter being removably secured to the projections d'. At the end of this plate are outwardly projected sockets d². D² represents a cover plate for the button raceway. This cover plate is provided with hinged members d³, embracing the sockets d² and pivotally supported or held in hinged position by 30 the pintle rod d⁴. The position of the jointed or hinged connection of the cover plate is such that when the plate is swung over to its position above the raceway it will serve as a top cover plate for the raceway, maintaining the buttons during their movement 35 down the smooth surface of the part D in their proper position and preventing the eyes of the buttons from escaping from the groove d.

40 45 Conveniently the cover plate D² is held in position by a spring D³ connected to the cover plate at a point intermediate its hinged connection and its outer edge. The spring is tensioned so that it will hold the cover plate 50 firmly in position over the fixed raceway member but permits the cover plate to be forced upward against the spring pressure and over to the position shown in Fig. 3, thus exposing the fixed raceway part and the 55 buttons therein contained. This is convenient for the reason that should it be desired to remove all the buttons from the raceway as in the event of clogging, removal can be easily accomplished. It is frequently desirable 60 in these machines to have the raceway adapted for different sized buttons. Heretofore it has been suggested to remove the button race or raceway tube and replace it with a smaller tube when a smaller button is to be 65 used. This is necessary in view of the fact

that there must be a proper relation between the supporting surface of the raceway and the top so as to prevent the button from rolling over or snapping out of the button eye groove.

70 By the employment of the swinging or movable plate D² this variance in its position with relation to the fixed part of the raceway may be readily accomplished. Any suitable means may be employed to limit the 75 downward movement of the movable cover plate, but in the present instance it has been found convenient to form on the under side of the plate D², somewhat back from its free edge, a flange d⁵, as shown in Fig. 6. This 80 depending flange assumes a position at the side of the stationary part of the raceway and in that position engages a squared gage plate E. The plate E is mounted fixedly 85 on a stem e of a hand wheel E', the stem passing through a bearing in the fixed part of the raceway, as shown in Fig. 6. The plate E may be four or more sided and is eccentrically mounted so that the distances 90 from the center to the respective edges are different, one from the other. By this means upon the turning of the gage plate with its shortest radii in a position directly below the flange d⁵, the spring D³ will force the cover plate downward until it rests firmly on the 95 edge of the gage plate. This will bring the cover plate in close proximity to the top of the fixed raceway member so that small buttons can be fed through the raceway. Should it be desirable to employ the machine 100 with buttons having larger heads it is only necessary to turn the hand wheel and the gage plate until one of its longer radii or sides is presented in opposition to the downward movement of the flange d⁵. Two 105 adjustments are shown, but four may be effected by the above described construction.

110 In machines of this character it often happens that a button being fed with its eye in position to receive the wire will be slightly canted so that the wire will strike the eye and tend to snap the button out of position. I have found it desirable to apply pressure to the top of the button in a manner which will not only seat the button properly but will tend to adjust it to its proper position against any slight deviation. To accomplish this, there is secured on the top of the plate D², an elongated spring F, having its rear or upper end fixedly secured to 115 the cover plate, and its lower end projecting slightly below the raceway directly above the button when the latter is grasped by the feeding and holding jaw C⁴. At the lower or free end of the spring F is secured a 120 holding block f provided on its under face with a V-shaped groove having its forward leg somewhat longer than its rear leg, as shown in Fig. 4. This block f is centrally positioned so that it will embrace the button 125 130

head, as shown in Fig. 7, and owing to the inclined surface on the lower face, the button will be prevented from tipping forward and the eye will therefor be properly centered and positioned for the subsequent operations of the machine. To remove the block f upon the completion of the stroke and to permit a subsequent button to be received in proper position, the following

10 instrumentalities are employed.

Keyed to the shaft of the bell crank C' is an arm G , Fig. 1, while on the head there is pivoted a trip lever G' having its forward end positioned directly below a sliding or reciprocating pin g , mounted in a suitable orifice extending vertically through the forward part of the head of the machine. The upper end of this pin is arranged to project directly below an outstanding projection f^2 on the spring F , while its lower end rests normally against the trip G' . Pivotally mounted on the trip member G' is a toothed member g^2 having its rear end projecting beyond the trip member G' and bent 25 back in a manner to overlie the upper inclined edge of the trip member. The tooth g^2 is extended rearward into the path of the arm G so that as the arm is rocked down it will strike the tooth member, thus deflecting 30 or tipping the trip member G' , forcing up the pin g and raising up the holding block f . The tooth g^2 is held in its normal position by a spring g^3 connected to a fixed part of the machine and the forward end of the 35 tooth, as shown clearly in Fig. 1.

Upon the operation of the treadle at the proper interval of time the end of the arm G engages the end of the tooth g^2 , forcing the pin g upward, raising the holding block. 40 At this moment, or thereafter, the staple is clenched and the next succeeding button is ready for feeding into position.

It is advantageous to have a stop for the buttons at the moment the holding block is 45 elevated and for this purpose two small yielding fingers h are employed, the same being extensions of a plate H , and are positioned on opposite sides of the holding block. The plate H is connected to the plate 50 D^2 by a hinged joint h' which is conveniently of a spring type, a tight spring being employed to normally hold the fingers in position to stop the forward movement of the row of buttons. The buttons, owing to 55 the slight resistance of the fingers, are easily moved past the same as they are advanced forwardly through the machine after the wire has been passed through the eye.

Associated with the button feed is a hopper 60 of the twin type, that is to say having compartments on the opposite sides of the center. This hopper is supported on a casting K extending from the head, there being pivoted to the lower end of the casting a 65 carrier K' , this carrier having an up and

down movement around its horizontal axis. The outer end of the carrier has pivoted thereon through a vertical axis, the hopper K^2 . By this means when it is desirable to turn the hopper completely around it is 70 turned on the vertical axis, while should it be desired to tip the hopper over it will be turned on the horizontal axis.

To couple the hopper in position of adjustment a suitable side spring L is employed, the same being fast to the stationary button race part, as shown in Fig. 1 and having an opening at its free end through which a small pin l passes, the same being projected from the hopper part. When it is 75 desired to release the hopper, the spring is moved outwardly to release the pin l . The outer end of the spring L is turned or bent to form a finger hold. Any convenient lever mechanism may be employed to operate the agitator within the hopper. Such mechanism may be similar to that shown in my aforesaid application for patent.

An advantage in positioning the head set- 80 ter and retaining fingers on the swinging cover plate for the raceway is that when it is desired to remove the buttons from the lower end of the raceway for any purpose this can be accomplished by swinging back the cover plate which will carry the head holder 85 and retaining fingers therewith, thus expos- 90 ing all the buttons in the raceway.

From the foregoing it will be evident that 95 the button feed can be readily and quickly adjusted for different sized buttons and that the centering and holding block for the button heads, owing to its flexible mounting, 100 may be quickly raised from a position where it will interrupt the downward movement of the succeeding button and likewise its 105 pressure on the button head is yielding. The light retarding fingers serve only to prevent the buttons from moving beyond the opera- 110 tive position and yield readily to the movement of the button after the staple has been formed and the button and staple carried forward.

Projecting forwardly from the front end 115 of the rocking lever C^3 in advance of the spring operated clamping jaw C^4 is a part C^5 , which constitutes a gage to indicate the point at which the machine will attach the button to the work.

Having thus described the invention, what 120 is claimed is:

1. In a button setting machine, a button raceway, and means for varying the size of the raceway to fit different sized button heads comprising a pivoted cover plate having its axis disposed on one side of the race- 125 way.

2. In a button setting machine, a button raceway, and means for varying the cross sectional area of the raceway to accommo- 130 date buttons of varying sizes comprising a

- cover plate overlying the raceway through which the buttons pass and being pivoted beyond one side thereof.
3. In a button setting machine, a button raceway, and means for adjusting the raceway to accommodate buttons of different sizes, said means comprising a pivoted cover plate vertically adjustable and capable of swinging movement out of the vertical plane 10 of the raceway to completely expose the same.
4. In a button setting machine, a button raceway, and a cover for the raceway hinged for adjustment uniformly from end to end 15 toward and from the raceway to vary the size of the raceway to accommodate buttons of different sizes.
5. In a button setting machine, a button raceway and a pivoted cover plate for the 20 raceway vertically adjustable to vary the size of the raceway and capable of lateral swinging movement out of the plane of the raceway to completely expose the same.
6. A button raceway for button setting 25 machines having a part adjustable to be swung laterally for adjusting the raceway to accommodate buttons of different sizes.
7. In a button setting machine, a button raceway having a longitudinally extending 30 wall hinged for adjustment uniformly from end to end to vary the size of the raceway to accommodate different size buttons.
8. In a button setting machine, a button raceway having a longitudinally extending 35 wall hinged for adjustment uniformly from end to end to vary the size of the raceway to accommodate different size buttons, and means for adjusting said wall.
9. In a button setting machine, a button 40 raceway having a longitudinally extending wall hinged for adjustment uniformly from end to end to vary the size of the raceway to accommodate different size buttons, means for adjusting said wall, said means 45 comprising an adjustable part, and means for yieldably maintaining said wall in engagement with said part.
10. In a button setting machine, a race- 50 way, a hinged cover therefor, and means for simultaneously raising or lowering each end of said cover relative to the race-way, said means comprising an adjustable part and a resilient member for maintaining the cover upon the adjustable part.
- 55 11. In a button setting machine, the combination with a raceway member, of a part on one side of the raceway member, a cover member having a part projecting beyond the raceway member and having a pivotal 60 connection with said first mentioned part for adjustment uniformly from end to end toward and from the raceway member, and means for maintaining the cover member in various positions of adjustment relative 65 to the raceway.
12. In a button setting machine, the combination with a raceway member, of a cover member having one side overhanging the raceway member, and means for engaging said overhanging side for moving the same 70 outwardly, said means comprising a rotatable plate and hinged connection on the opposite side of said raceway for supporting the cover member.
13. In a button setting machine, the combination with a raceway comprising two 75 relatively movable members, and a hinge connection between the members for varying the relative position between the members to vary the size of the raceway to accommodate buttons of different size, said hinged means being located at a point to permit one of the movable members to be swung entirely beyond the vertical plane of the other.
14. In a button setting machine, a race- 80 way having a hinged upper part, with means located at the side of the raceway for adjusting the said hinged part, said means comprising a spring member and a manually operable part adapted to adjust each 85 end of the hinged part simultaneously.
15. In a button setting machine, a button raceway part, a cover plate for the raceway part adjustably mounted with relation to the raceway part, and an adjustable eccentric for limiting the downward movement of the cover plate toward the raceway part. 90
16. In a button setting machine, the combination with a relatively fixed raceway part, of a hinged cover plate, a spring for 95 maintaining the cover plate in normal position, and means for limiting the downward movement of the cover plate, said spring and cover movement limiting means being located entirely upon one side of the race- 100 way.
17. In a button setting machine, a race- 105 way part having a button eye groove therein, a cover plate part adjustably mounted with relation to the said other part, a rotatable eccentric for limiting the downward movement of the cover part toward the other part, and means for adjusting the eccentric. 110
18. In a button setting machine, a race- 115 way part having a button eye groove and a swinging cover part pivoted to the machine on one side of the button eye groove with means for limiting the swinging movement of the cover part comprising a stop member.
19. In a button setting machine, a race- 120 way, a removable top for the raceway, a head holder carried by the top, and yielding fingers positioned on opposite sides of the holder and secured to the said top.
20. In a button setting machine, the combination with a raceway member through 125 which the buttons pass, of setting instrumentalities and a wire feed, an adjustable guide overlying the button raceway, and means for adjusting said guide relative to 130

the raceway member, said means simultaneously raising each end of the guide to move the same a uniform distance throughout its length relative to the raceway member, said 5 adjusting means comprising a rotatable member carrying an eccentrically mounted part thereon.

21. In a button setting machine the combination with a staple forming and driving mechanism and a wire feed, of means 10 for gripping a button eye to support the same to receive the staple wire and a gage carried by said supporting means for indicating the point at which the machine will 15 attach the button to the work.

22. In a button setting machine, a button raceway, a cover for the raceway adjustable toward and from the raceway to vary the

size thereof to accommodate different size buttons, a holding device to engage the head 20 of a button and retain the same in position to receive the staple wire, means for periodically moving said holding device to release the button therefrom, and yieldable holding means for retaining the following buttons 25 when said holding device is moved out of engagement with the button, said holding device and the last mentioned holding means both being carried by and adjustable toward and from the raceway with the cover. 30

In testimony whereof I hereunto affix my signature in the presence of two witnesses.

JOHN KELLY.
